UNITED STATES PATENT OFFICE.

LAWRENCE C. STEELE, OF VANDERGRIFT, PENNSYLVANIA.

PLATE-BAR-HEATING FURNACE.

941,738.

Specification of Letters Patent. Patented Nov. 30, 1909.

Application filed February 8, 1909. Serial No. 476,784.

To all whom it may concern:

Be it known that I, LAWRENCE C. STEELE, a resident of Vandergrift, in the county of Westmoreland and State of Pennsylvania, have invented a new and useful Improvement in Plate-Bar-Heating Furnaces; and I do hereby declare the following to be a full, clear, and exact description thereof.

This invention relates to metal heating furnaces and more especially to furnaces for heating metal blanks, such as plate bars, small billets and the like.

The object of the invention is to provide a furnace for this purpose in which an absolutely uniform temperature can be maintained in all portions of the heating chamber, and one in which the bars, etc., are introduced and withdrawn with practically no loss of heat.

20 My invention comprises the novel features hereinafter set forth and claimed.

In the accompanying drawings Figure 1. is a vertical section through my improved furnace; Fig. 2 is a horizontal section taken 25 on the line 2—2 Fig. 1, and on line 2^a—2^a. Fig. 3 showing portions of the hearth or floor broken away; Fig. 3 is a vertical section on the line 3—3 Fig. 2; Fig. 4 is a detail horizontal section showing a slight modification; and Fig. 5 is a section on line 5—5 Fig. 1.

The furnace is of the circular type, having the walls 1, roof 2, and base or floor 3, enclosing the heating chamber 4. In this 35 chamber is a traveling or rotating annular hearth 5 mounted on balls 6, and driven in any suitable way, such as from the gear 7 on shaft 8. The chamber walls are also provided with the vestibule 10 by means of 40 which the bars to be heated are introduced and withdrawn. This vestibule forms an inclosure which is so arranged as to prevent the cold air from finding its way to any extent into the furnace during the charging 45 of the furnace or the withdrawal of the bars therefrom. To this end the doors 11 and 11^a are employed. Said doors are hinged by suitable hinges 10^a to the partitions 10^b which separate the vestibule from the heating 50 chamber of the furnace. Said vestibule has the top 10^c and rear wall 10^d. These doors 11 and 11^a swing freely so that they will be opened by the contact of the bars

therewith and they will drag over said bars so as to prevent the entrance of cold air and 55 will resume their normal positions when the bars have passed. They may be formed of metal lined with asbestos. This vestibule is of sufficient size to admit of a suitable charging device, a cold pair of bars being introduced at the same time a heated pair is removed. This apparatus, however, forms no part of my invention.

At the center of the furnace is the mixing and combustion chamber 12, inclosed by the 65 annular bridge wall 13 which projects forwardly some distance above the hearth 5. Communicating centrally with the mixing chamber is the gas port 14 communicating with the gas main 15. In the masonry surrounding the lower part of the mixing chamber 12 is an annular air passage 16 communicating by means of a series of ports 17 with said combustion chamber, and in turn being supplied with air by means of the 70 75 radially arranged air ports 18 extending through the masonry to the outside of the furnace. The air coming in through these ports enters the combustion chamber through the ports 17 and is there mixed with gas 80 coming through port 14 and is there ignited. The flame passes up over the bridge wall 13, and is drawn outwardly in the form of a mushroom or umbrella to the outlet openings 85 20 arranged at the periphery of the furnace chamber, namely, in the walls 1, and being uniformly spaced so as to get a uniform distribution of the heat and flame. These outlet ports 20 communicate with passages 21 extending downwardly and then radially 90 inwardly as at 22, where they communicate with an annular passage 23, surrounding the gas port 14, said annular passage communicating with flue 24 which leads to the stack.

The waste heat flues 22 are formed in the masonry preferably at a lower plane than the air inlet ports, 18, and as the masonry becomes heated from these waste gases the air coming through the ports 18 will likewise become heated. The heating effect on the incoming air is very greatly increased by extending the outlet ports radially inwardly as far as possible, thus enabling the waste gases to impart most of their heat to 100 105 the masonry. If desired, the air inlet ports

18 may be arranged parallel with the passages 22, as shown, for instance, in Fig. 4, thus bringing the air passages as close to the waste gas passages as possible, giving the air 5 a high degree of heat.

Flues 26 are formed in the walls 10^b of the vestibule which communicate with the stack-flue to draw or carry off any cold air which may enter when the doors are opened before 10 said air finds its way into the heating chamber.

In the operation of the furnace the bars 25 will be introduced into the vestibule 10 upon the hearth 5, and will be carried by the latter into the heating chamber. In passing from the vestibule into the heating chamber the bars 25 (heated in pairs the one resting on the other) will come into contact with the door 11 and said door will yield and swing 15 back to permit the bars to enter the heating chamber, said door dragging over the top of the bars and preventing the entrance of the air to any extent until said bars have passed beyond the reach of said door where- 20 upon said door drops back to its normal position. At the same time that cold bars are being introduced as above a pair of hot bars having passed through the furnace come 25 in contact with the door 11^a and said door is opened enough to permit the bars to enter the vestibule in position to be removed therefrom. In this manner the bars are introduced and withdrawn from the furnace with little or no cold air being admitted and the 30 temperature can be maintained at an even heat which gives better and more uniform results.

The air and gas are ignited in the chamber 12, and the flame and heat are drawn over 40 the bridge wall 13 and spread out uniformly, being drawn through the peripheral outlets

20, thus giving a uniform and even distribution of the flame.

What I claim is:

1. A heating furnace comprising a circular chamber, an air and gas inlet through the center of the floor of said chamber, a rotating annular hearth in said chamber, and a series of outlet openings at the periphery of the furnace chamber. 45

2. A heating furnace for plate bars comprising a circular chamber, an endless traveling hearth therein, a radially arranged vestibule through which the said hearth travels, and doors separating said vestibule from 50 said furnace chamber. 55

3. A heating furnace for plate bars, comprising a circular chamber, an endless traveling hearth therein, a radially arranged vestibule through which the hearth travels, and 60 automatically operating doors separating said vestibule from said furnace chamber. 65

4. A heating furnace for plate bars, comprising a circular chamber, an endless traveling hearth therein, a radially arranged vestibule through which said hearth travels, and swinging doors separating said vestibule from 70 said furnace chamber. 75

5. A heating furnace comprising a heating chamber, a traveling conveyer therein, 70 a vestibule through which said conveyer travels, a door separating said vestibule from said heating chamber, and an escape flue formed in the walls of said vestibule adjacent to said door. 75

In testimony whereof, I the said LAWRENCE C. STEELE have hereunto set my hand.

LAWRENCE C. STEELE.
